UNITED STATES PATENT OFFICE.

WILLIAM FONDILLER, OF NEW YORK, N. Y., ASSIGNOR TO WESTERN ELECTRIC COMPANY, INCORPORATED, OF NEW YORK, N. Y., A CORPORATION OF NEW YORK.

PHANTOM LOADING-COIL.

1,206,524.

Specification of Letters Patent. Patented Nov. 28, 1916.

Application filed December 2, 1915. Serial No. 64,672.

To all whom it may concern:

Be it known that I, WILLIAM FONDILLER, a citizen of the United States, residing at New York, in the county of New York and 5 State of New York, have invented certain new and useful Improvements in Phantom Loading-Coils, of which the following is a full, clear, concise, and exact description.

This invention relates to loading of phantom circuits in telephony. Its object is to simultaneously load two physical circuits and the derived phantom circuit while maintaining a high degree of balance, and securing also a desired ratio of phantom circuit inductance to physical circuit inductance, which ratio cannot be made sufficiently high in the various single unit loading schemes which have been proposed. These objects are accomplished by placing windings in a 20 novel manner upon a new type of magnetic structure.

The invention will be more particularly described in connection with the drawings, wherein—

25 Figure 1 is a general view of the new type of magnetic structure proposed; Fig. 2 is a circuit diagram showing the method of connecting in the physical circuits; and Fig. 3 is a diagram showing in another way the 30 winding scheme of the structure.

Referring to Fig. 1, 5 and 6 represent two toroidal loading coils located one above the other and separated by the four magnetic yokes or pillars 7. The cores of these coils 25 may be of any suitable magnetic material, and are preferably formed of finely divided iron, the individual particles of which are insulated from one another, the core structure being molded by high pressure into the 40 required form, in the manner described and claimed in an application for patent in the name of J. B. Speed, Serial No. 89,409, filed April 6, 1916, assigned to the same assignee as the present application. The yokes 7 may 45 be made of iron stampings. It is clear that the structure here shown has six possible simple magnetic circuits, and that these are symmetrically arranged, corresponding roughly to the six faces of a cube. Since 50 there are six effective line conductors in use, two in each pair of physical circuits, and effectively two in the derived circuit, it is clear that these may be disposed upon this structure in a symmetrical way, so that no 55 electromagnetic or electrostatic unbalances

shall occur. In this invention this is accomplished by so winding the structure that the upper and lower faces shall contain the fluxes used to load the phantom circuit, and the other faces, in pairs of opposite members, shall contain the magnetic circuits for the physical circuit fluxes. By inspection of the magnetic circuits, it appears that the inductance added to the phantom circuit may be made to have any desired ratio to that 65 added to the physical circuits.

Fig. 2 shows diagrammatically the connections of the circuits. Here 1 and 2 represent the line conductors of one physical circuit, and 3 and 4 those of the other physical circuit. The phantom circuit is derived from these in the usual manner, namely, by making use of 1 and 2 in parallel as one conductor, and of 3 and 4 in parallel as the other conductor. 5 and 6 are the two loading 75 coils which have been described in connection with Fig. 1; these are shown in the same plane for clearness in this drawing, but are actually placed one above the other and connected by means of the yokes 7, which are 80 here shown in section. Each of the quadrants of these cores is wound with a winding such as 8. One physical circuit conductor 3 passes through the winding 8, and from there through the winding 9 upon the other loading coil. Similarly, line conductor 1 of the other side circuit passes through winding 10 and also through winding 11 upon the other loading coil. The other physical circuit conductors are similarly connected to 85 other windings. Inspection of this method of winding will show that when line conductors 1 and 2, for example, are used in parallel to form one conductor of the phantom circuit, and 3 and 4 in parallel to form the other conductor, the fluxes due to currents in these parallel conductors will lie in circular paths in each core. On the other hand, in the normal operation of the side circuits by 90 themselves, currents in the conductors 1 and 2, for example, are in opposite directions, and the flux linked with either physical circuit will lie in paths which pass along one-fourth of the upper loading coil in one direction, down a magnetic yoke, along one-fourth of the lower loading coil in the opposite direction and up a magnetic yoke to the upper loading coil. Flux linked with the 95 same side circuit will also lie in a similar magnetic circuit located diametrically opposite.

site. It will be apparent that by this arrangement the fluxes due to the two physical circuits are independent, as are also those due to either physical circuit and the phantom circuit. Further, since the flux linked with the phantom circuit lies in a path of low magnetic reluctance and the relative reluctance to the physical circuit flux is adjustable, the inductance added to the phantom circuit may be made to have any desired ratio to that of the physical circuit. Fig. 3 shows, in another form, the method of connection of these cores. In this figure the two loading coils are shown as of different diameter, in order to show the mutual relations in a plane drawing. In all of these figures, like numerals refer to corresponding parts.

What is claimed is:

1. The combination of two physical circuits, a derived phantom circuit, two loading coils each with four windings and means for causing the flux between the two loading coils to link with and load the said physical circuits, the phantom loading being provided by flux lying wholly within said loading coils.

2. The combination of two physical circuits, a derived phantom circuit, two loading coils each with four windings and four mag-

netic yokes joining said coils and providing paths for the flux used to load the said physical circuits.

3. The combination, with two physical circuits and a phantom circuit, of a loading unit comprising two toroids separated by four symmetrically placed pillars which divide the toroids into quadrants, and a winding upon each of said quadrants, said windings being so connected that fluxes due to the phantom currents shall lie wholly in said toroids, and fluxes due to the physical circuit currents lie in paths each containing two quadrants and two pillars.

4. The combination, with two physical circuits and a phantom circuit, of two loading coils having quadrantal windings of which pairs of diagonally opposite windings are connected respectively to the two physical circuits, and four magnetic yokes joining said coils at winding terminals and adapted to carry flux due to the physical circuit currents, while fluxes due to the phantom circuit currents lie in paths wholly in said loading coils.

In witness whereof, I hereunto subscribe my name this 30th day of November A. D., 1915.

WILLIAM FONDILLER.
